No. 612,661.

Patented Oct. 18, 1898.

Z. A. CURTIS.

WIRE STRETCHER.

(Application filed July 2, 1898.)

(No Model.)

UNITED STATES PATENT OFFICE.

ZENAS ALBERT CURTIS, OF HANSFORD, TEXAS.

WIRE-STRETCHER.

SPECIFICATION forming part of Letters Patent No. 612,661, dated October 18, 1898.

Application filed July 2, 1898. Serial No. 685,061. (No model.)

To all whom it may concern:

Be it known that I, ZENAS ALBERT CURTIS, of Hansford, in the county of Hansford and State of Texas, have invented certain new and useful Improvements in Wire-Stretchers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention consists in certain new and useful improvements in wire-stretchers.

The object of the invention is to provide a stretcher simple, cheap, and durable of construction, composed of a minimum number of parts, and exceedingly quick and efficient in operation.

A further object of the invention is to provide a wire-stretcher that may be stationed at any point along the line of fence to construct, tighten, or splice loose or broken strands.

A further object of the invention is to provide means for holding the wire taut while the stretching-lever is taking up additional slack preparatory to further stretching of the wire.

To these and further ends the invention consists in certain novel features of construction and in combination of parts more fully described hereinafter and particularly pointed out in the claims.

Referring to the accompanying drawings, Figure 1 is a perspective view of my improved wire-stretcher in operative position. Fig. 2 is a front elevation thereof. Fig. 3 is a rear elevation. Fig. 4 is a side elevation. Fig. 5 is an elevation of the two members of a clamping-block, and Fig. 6 is a perspective detail view of the detached members of the wire-clamps.

Referring to the letters on the drawings, a indicates the fence-post, and b fence-wires stretched and secured to the post.

c indicates the frame of my stretcher, which consists of a standard of suitable size, shape, and material, provided with an anchor or securing-pin d, adjustably secured to one side of the frame by bearing-bands e. The anchor is designed to be driven into the ground and

the frame is adjusted vertically to bring its upper end at the proper height to receive the wire.

55

f indicates a longitudinal groove extending along the front face of the standard, and g indicates a T-shaped aperture through the frame adjacent to its upper end for the accommodation of a pair of horizontal grooved rollers h and a vertical roller i, similarly grooved, the first-named rollers being located with their peripheries contiguous and projecting slightly beyond the rear face of the standard and the last-named or vertical roller 60 being below the horizontal rollers and having its periphery contiguous to its front face.

j indicates a spring-actuated holding-lever pivoted in a bracket k upon the standard and provided with a beak l, extending into the 65 grooves of the roller i.

m indicates a long stretching-lever pivoted at its upper end within the groove f and provided with a projection n, to each side of which are secured clamping-blocks o, having L-shaped ledges p, and eccentrically-pivoted clamps q, having longitudinal ledges, between which and the ledges p the flexible ropes or chains r, passing between the rollers h and over the roller i, are designed to be clamped. 75

s indicates a pair of wire-clamps having corrugated jaws secured at the outer ends of the ropes or chains r and designed to be employed in a manner hereinafter described. These clamps are provided with somewhat-enlarged 80 ends u and handles v, having apertures therein, the said ends being provided with rearwardly-opening recesses w, in which are journaled small antifriction-rollers y.

a' indicates lateral ledges along one side of 90 each of the ends u, and b' indicates clamping-levers pivoted to the clamp above said ledges and designed to clamp the wires thereupon.

In practice if it is desired to string a wire leader or strand one end is secured to a post, 95 and a second post is planted at a proper distance to give a fence-panel of the required length. My stretcher is then placed upon the side of the second post. The wire and the stretching-lever having been elevated, the free 100 ends of the ropes or chains r are secured to the clamping-blocks o by the clamps q. The clamp s is then passed around one side of the post and is attached to wire adjacent to its

end. The stretching-lever *m* is then depressed and the slack of the wire is taken up. The holding-lever will now bear upon the rope or chain passing over the roller *i* with sufficient pressure to hold the wire while the lever *m* is elevated. The depression of the lever *m* will cause the wire to be properly stretched, and it may be stapled to the post in the usual manner.

- 10 5 If it is desired to splice a broken wire, the device may be properly positioned at the break by sticking the anchor *d* into the ground, and the clamps *s* having been connected to the adjacent ends the depression of the lever *m* will draw them together to permit of their being twisted together or otherwise connected. In like manner the slack of a stringer or leader may be taken up by extending the clamps *s* upon opposite sides of the post and 15 20 engaging the wires in the recess *w* and against the rollers *y*. The actuation of the stretching-lever will loop the slack of the wire up to the post, to which it may be secured by a separate wire or by staples.
- 25 30 35 It will thus be seen that I have invented a simple and efficient wire-stretcher designed for fence construction or repairing which may be easily operated and which by reason of its manner of use will facilitate the stretching of wire strands in a minimum of time and with a maximum economy of labor.

What I claim is—

- 1. In a wire-stretcher, the combination with a frame, of a stretching-lever pivoted thereon and provided with clamps, rollers journaled in the frame and wire-clamps provided with ropes or chains passing over the rollers and engaged by the clamps of the lever, substantially as specified.
- 35 40 2. In a wire-stretcher, the combination with a frame, of a pair of horizontal grooved rollers journaled therein, a vertical roller below the

horizontal rollers, a stretching-lever provided with clamps, a pair of wire-clamps provided with ropes or chains passing between the horizontal rollers and over the vertical roller and clamped to the lever and a spring-actuated holding-lever bearing against the ropes or chains as they pass over the last-named roller, substantially as specified.

45 50 5. In a wire-clamp, the combination with a handle and enlarged head provided with a lateral ledge and with a rearwardly-opening recess in one edge, of an antifriction-roller within the recess and a clamping-lever pivoted above the lateral ledge, substantially as specified.

55 60 6. A wire-stretcher comprising the frame, a stake or anchor movable on said frame, a pair of horizontal grooved rollers journaled in said frame, a stretching-lever having clamping-blocks, a pair of wire-clamps carried by ropes or chains passing between said rollers and attached to the stretching-lever by means of the said clamping-blocks, substantially as 65 specified.

70 75 7. A wire-stretcher comprising the frame, an anchor carried thereby, a stretching-lever, clamping-blocks thereon, rollers in said frame, wire-clamps, ropes or chains passing between and over said rollers and attached to the stretching-lever by means of said clamping-blocks, a spring-actuated holding-lever pivoted near the top of the frame above the vertical roller and adapted to securely hold the ropes or chains carrying the wire-clamps on said roller for the purpose set forth.

In testimony that I claim the foregoing as my own I affix my signature in presence of two witnesses.

ZENAS ALBERT CURTIS. [L. S.]

Witnesses:

WALLACE MCKAY,
F. J. HOWARD.
